Patented Dec. 23, 1969

216,363

VALVE FOR FIRE EXTINGUISHERS

Ignatius Nurkiewicz, Princeton, N.J., assignor to
Stop-Fire, Inc., Monmouth Junction, N.J.

Filed Jan. 28, 1969, Ser. No. 15,538

Term of patent 14 years

Int. Cl. D23—01

U.S. Cl. D23—19

FIG. 1

FIG. 3

FIG. 2

FIG. 4

FIG. 5

FIGURE 1 is a perspective view taken from the top, front and side of a valve showing my new design;
 FIGURE 2 is a front elevational view thereof;

FIGURE 3 is a top plan view thereof, a portion being broken away for convenience of illustration;

FIGURE 4 is an elevational view from one side thereof; and

FIGURE 5 is an elevational view from the other side thereof.

I claim:

The ornamental design for a valve for fire extinguishers, as shown.
